FRANK L. DODGSON, OF ROCHESTER, NEW YORK, ASSIGNOR TO GENERAL RAILWAY SIGNAL COMPANY, OF GATES, NEW YORK, A CORPORATION OF NEW YORK.

ABSOLUTE PERMISSIVE BLOCK-SIGNALING SYSTEM.

1,384,521.

Specification of Letters Patent. Patented July 12, 1921.

Application filed October 15, 1915. Serial No. 56,047.

To all whom it may concern:

Be it known that I, FRANK L. DODGSON, a citizen of the United States, and resident of the city of Rochester, in the county of 5 Monroe and State of New York, have invented a new and useful Absolute Permissive Block-Signaling System, of which the following is a specification.

This invention relates to circuits for block 10 signaling systems for governing railway traffic, and more particularly to circuits which find a very useful application in block signaling systems for single track roads.

One of the objects of this invention is to 15 devise an arrangement of circuits for single track block signaling systems by means of which a train entering upon a stretch of single track between two passing sidings will cause signals to be displayed which will prevent 20 the entrance of a train on said stretch of track from the other end thereof and which will afford adequate head-on and following protection for the train as it passes through said stretch of track without, however, unnecessarily delaying traffic.

A further object of the invention is to 25 devise an arrangement of controlling circuits for a block signaling system, whereby a signal may be controlled effectively by 30 simple and durable apparatus and caused to assume different aspects according to the direction in which the train is traveling as it passes said signal.

A further object of the invention is to 35 accomplish the objects enumerated and other objects which will appear more fully as the description of the invention progresses by means of apparatus and controlling circuits therefor which are constructed in accordance 40 with principles found through long trial to be safe and reliable.

Further objects and advantages will appear as the description of the invention progresses, and the novel features of the invention will be particularly pointed out in 45 the appended claims.

In general, the invention consists in providing a suitable arrangement of electrical devices and controlling circuits therefor, in 50 connection with the well known block signaling system employing normally closed track circuits, whereby these devices are respon-

sive to the direction of the movement of trains over a given part of the track.

The invention further consists in the 55 parts, and in the arrangements and combinations of parts, together with the controlling circuits therefor, which are set forth fully at length hereinafter.

In describing the invention in detail, reference is had to the accompanying drawing, wherein I have illustrated a preferred physical embodiment of my invention, and wherein like characters of reference designate corresponding parts throughout the 60 several views, and in which:

The single figure is a diagrammatic illustration of a stretch of single track having passing sidings at each end, signals for governing traffic over said stretch in both directions, together with the electrical devices and controlling circuits therefor embodying this invention, the operating parts of said devices and said controlling circuits being shown in their normal conditions existing 70 when there is no train present on any part of said stretch of track.

Referring to the accompanying drawing, the two track rails 1 and 2 of the stretch of track between the passing sidings S are 80 divided by suitable insulating joints 3 into a series of track sections of which four are shown and designated A, B, C, and D. Each of these track sections has a track battery 4 connected across the track rails 1 and 2 at 85 one end of said sections, and at the other ends of said sections track relays 5, 6, 7, and 8 are connected across said track rails. The track battery 4 and the track relay of each track section, together with the track rails 90 thereof constitute the well known normally closed track circuit, the operation of which will be clearly understood by those skilled in the art of railway signaling without further explanation. The two track sections B 95 and C together form one of the so called blocks, and the combined length of said two track sections is substantially the same as the length of each of the track sections A and D, so that in effect, there are three blocks 100 A, BC, and D. Traffic over this stretch of track may be in either direction as indicated by the arrows X and Y.

At the lefthand end of the block A is

located a signal 9 which governs traffic in the direction indicated by the arrow X; and located at the lefthand end of the block BC is a similar signal 10 governing traffic in the same direction. At the righthand end of the block D is a signal 12 which governs traffic in the direction indicated by the arrow Y, and at the righthand end of the block BC is a similar signal 11 governing traffic in the same direction. The signals 9 and 12 at the ends of the stretch of track are of a type commonly known as absolute signals, that is, these signals must be rigidly observed by the engineers and should not be passed, when indicating stop or danger, unless with great care and strictly in accordance with the prescribed rules of safety. The intermediate signals 10 and 11, however, are of the type commonly known as permissive signals, that is, these signals may be passed, when indicating stop or danger, without exercising the same degree of care required when passing the absolute signals 9 and 12. The different aspects of the signals 9 and 12, and the signals 10 and 11, which are necessary to enable the engineer to differentiate between them, may be obtained in various ways; but in the particular arrangement illustrated, the absolute signals 9 and 12 have squared-ended semaphore blades, while the permissive signals 10 and 11 have the ends of their semaphore blades pointed. Obviously, the different aspects of the absolute signals and the permissive signals may be obtained in other ways, as by the addition of other semaphores to the absolute signals; and also instead of semaphores, lights of different colors or a series of lights having different positions may be used to obtain the different aspects.

These signals may be of any well known and approved type which is used in single track or in double track signaling, and primarily comprises an operating motor of any appropriate construction for moving the semaphore blade from a normal biased position, which may be termed the stop position, to an operated position, which may be termed a caution position; and further comprises means which is effective upon the proper placing of the semaphore in its operated position to retain it in that position, together with suitable circuit controllers operated in conjunction with the movement of the semaphore to control the various operating and holding circuits for the signal. In the particular embodiment of the invention illustrated, the signals shown have a 45 degree caution position and a horizontal stop position, this being done in order to avoid the confusion of the extra controlling circuits incident to the use of three-position signals or of two two-position signals arranged as home and distant sig-

nals; but it is to be understood that it is fully contemplated according to this invention to use appropriate controlling circuits with each signal whereby the preceding signal is caused to assume a caution aspect, the signals in that case having a vertical position indicating proceed at unlimited speed. In practical installations, other permissive signals may be located at the lefthand ends of the blocks A and BC for governing traffic in the direction indicated by the arrow Y, and at the righthand ends of the blocks BC and D for governing traffic in the direction indicated by the arrow X; but since the controlling devices and circuits for these other signals can be easily determined by one skilled in the art of railway signaling from analogy to the controlling devices and circuits of such signals as are shown, and since the addition of the controlling devices and circuits for these other signals would complicate the drawing materially, it has been deemed best to omit the showing of these other signals from the drawing.

Associated with each signal is a relay, hereinafter termed a line relay, said relays for the signals 9, 10, 11, and 12 being designated 13, 14, 15, and 16, respectively. Associated with each intermediate permissive signal 10 and 11 is a relay, hereinafter termed a stick relay, said stick relays being designated 17 and 18 respectively for the signals 10 and 11. Also, associated with each signal is a suitable source of electric current, as a battery, said batteries for the signals 9, 10, 11, and 12 being designated 19, 20, 21, and 22, respectively; and extending the entire length of the stretch of track is a common wire 25 to which one terminal of each of said batteries is connected by two wires. For simplicity the different circuits hereinafter traced will be traced from the other terminals of the batteries 19, 20, 21, and 22 (marked positive) back to the common wire 25, it being observed that the common wire 25 serves to complete these different circuits in each case.

Although certain relays are herein designated as track relays, certain others as line relays and certain others as stick relays, it is not to be inferred from this that there is in reality any essential or fundamental difference between the relays so designated, because each of these relays are of the well known and ordinary type used for signaling purposes, and vary, not because of differences in their construction, but rather because of the different uses to which they are put.

The track relays 5 and 8 of the block A and D each have three armatures 34, 35, and 36, and 37, 38 and 39, respectively, which are operated thereby in the well known manner and which are designated according to

established convention; and the line relays 13 and 16 of the blocks A and D each have an armature 40 and 41, respectively. The track relays 6 and 7 of the track sections B and C each have two armatures 42 and 43, and 44 and 45, respectively; each of the line relays 14 and 15 of the track sections B and C have four armatures, 46, 47, 48 and 49, and 50, 51, 52, and 53, respectively; and each of the stick relays 17 and 18 of the track sections B and C have three armatures, 54, 55, and 56, and 57, 58, and 59, respectively.

In order to make the operation of the system clear two cases will be assumed, first, that the train enters the stretch of track traveling in the direction indicated by the arrow X; and second that another train at another time enters the stretch of track traveling in the direction indicated by the arrow Y. Assuming that the train enters the block A moving in the direction of the arrow X, the stretch of trackway being entirely clear of other trains, the wheels and axles of said train being of comparatively low resistance will shunt the track relay 5 of the block A and cause its armatures to drop to their lower position. The armature 35 of the track relay 5 in dropping interrupts a normally closed circuit for energizing the line relay 13, which circuit is as follows:

Circuit Number One.

Commencing at the positive terminal of the battery 20, conductors 60, 61, 62, and 63, armature 47 of the line relay 14 in its upper position, conductors 64 and 65, armature 35 in its upper position, conductor 66, line relay 13 and conductors 67, 68, and 27 back to the common wire 25.

40 The supply of current to the line relay 13 being interrupted, the armature 40 of this relay drops and interrupts a normally closed circuit which supplies current to the motor of the signal 9 to hold that signal in its operated position, thereby causing said signal to assume its biased stop aspect. This circuit may be traced as follows:

Circuit Number Two.

50 Commencing at the battery 19, conductors 70 and 71, armature 40 of the line relay 13 in its upper position, conductor 72, signal 9, conductors 73, 68, and 26 back to the battery 19.

55 The dropping of the armature 34 of the track relay 5 interrupts a normally closed circuit for supplying current to the line relay 15 associated with the signal 11, said circuit being as follows:

Circuit Number Three.

Commencing at the battery 19, conductors 70, 74, and 75, armature 34 of the track relay 5 in its upper position, conductor 76, armature 56 of the stick relay 17 in its lower position, conductor 77, armature 42 of the track relay 6 in its upper position, conductor 78, armature 45 of the track relay 7 in its upper position, conductor 79, line relay 15, and conductors 80, 81, 82, and 31 back to the common wire 25.

65 The supply of current to the line relay 15 being cut off, the armature 50 of this relay will drop and interrupt the circuit which normally supplies current to the signal 11 75 and holds said signal in its operated position, thereby causing said signal to assume its biased stop position, said circuit being as follows:

Circuit Number Four.

80 Commencing at the battery 21, conductors 83, 84, 85 and 86, armature 50 of the line relay 15 in its upper position, conductor 87, signal 11 and conductors 88, 81, 82 and 31 85 back to the common wire 25.

When the line relay 15 is deenergized, its armature 51 drops and interrupts a circuit Number Five for normally energizing the line relay 16, which circuit may be traced as follows:

Circuit Number Five.

90 Commencing at the battery 21, conductors 83, 84, 85 and 89, armature 51 of the line relay 15 in its upper position, conductors 90 and 91, armature 38 of the track relay 8 in its upper position, conductor 92, line relay 16, and conductors 93, 94 and 33 back to the common wire 25.

100 The line relay 16 being deenergized, its armature 41 drops and interrupts a circuit Number Six which supplies current to the signal 12 and holds it in its operated position, thereby causing said signal 12 to assume its biased stop position, said circuit Number Six for the signal 12 being as follows:

Circuit Number Six.

110 Commencing at the battery 22, conductors 95 and 96, armature 41 of the line relay 16 in its upper position, conductor 97, signal 12, and conductors 98, 94 and 32 back to the battery 22.

115 From the foregoing it can be seen that when the train enters the stretch of single track moving in the direction indicated by the arrow X, the signal 9 behind the train will assume the stop or danger aspect and the two signals 11 and 12 governing traffic in the opposite direction will also assume their stop aspects. The signal 12 prevents the entrance of another train into the stretch of trackway, the signal 11 gives the train 120 head-on protection, while the signal 9 gives the train following protection. When the train enters the block A and deenergizes the

track relay 5, the armature 36 of said track relay drops and closes a preliminary energized circuit for the stick relay 17, which circuit is as follows:

5 *Circuit Number Seven.*

Commencing at the battery 19, conductors 70, 74, and 100, armature 36 of the track relay 5 in its lower position, conductors 101 and 102, armature 48 of the line relay 14 in its upper position, conductors 103 and 104, stick relay 17 and conductors 105, 106 and 29 back to the common wire 25.

The energization of the stick relay 17 15 raises its armature 54 and completes a maintaining circuit for said stick relay 17 as follows:

Circuit Number Eight.

20 Commencing at the battery 19, conductors 70, 74, and 100, armature 36 of the track relay 5 in its lower position, conductors 101, 107 and 108, armature 54 of the stick relay 17, conductors 109 and 104, stick relay 17, 25 and conductors 105, 106 and 29 back to the common wire 25.

When the first pair of wheels and axle of the train enter the track section B, the track relay 6 is shunted and its armatures drop. 30 The armature 42 opens another break in the circuit Number Three and maintains the line relay 15 deenergized so that, although the train leaves the block A and the track relay 5 becomes reenergized, nevertheless, signals 11 35 and 12 will remain in their biased stop position.

The armature 43 of the track relay 6 40 breaks a circuit Number Nine which normally energizes the line relay 14 and which can be easily traced by analogy to a circuit Number Three hereinbefore set forth, as follows:

Circuit Number Nine.

45 Commencing at the battery 22, conductors 95, 110, and 111, armature 37 to the track relay 8 in its upper position, conductor 112, armature 59 of the stick relay 18 in its lower position, conductor 113, armature 44 of the track relay 7, conductor 114, 50 armature 43 of the track relay 6 in its upper position, conductor 115, line relay 14, conductors 116, 117, 106, and 29 back to the common wire 25.

55 The deenergization of the line relay 14 causes its armature 46 to drop and interrupt a circuit Number Ten analogous to the circuit Number Four which normally maintains the signal 10 in its operated position, 60 thereby causing said signal 10 to assume its biased stop position, said circuit being as follows:

Circuit Number Ten.

65 Commencing at the battery 20, conductors

60, 61, 62, and 118, armature 46 of the line relay 14 in its upper position, conductor 119, signal 10 and conductors 120, 117, 106, and 28 back to the battery 20.

When the armature 48 of the line relay 70 14 drops, it interrupts the energizing circuit Number Five for the stick relay 17; but the dropping of the armature 49 of the line relay 14 completes another maintaining circuit for the stick relay 17 as follows: 75

Circuit Number Eleven.

Commencing at the battery 20, conductors 60, 61, and 121, armature 49 of the line relay 14 in its lower position, conductors 80 122 and 108, armature 54 of the stick relay 17 in its upper position, conductors 109 and 104, stick relay 17, and conductors 105, 106 and 29 back to the common wire 25.

The armature 47 of the line relay 14 in 85 dropping would interrupt the circuit Number One for the line relay 13, except for the fact that the stick relay 17 is energized and its armature 55 is in its upper position, so as to complete a shunt comprising the conductors 123 and 124 for the contacts of said armature 47, so that when the train has entirely left the block A and the track relay 5 has been energized to raise its armature 35, current can flow from the battery 20 and 95 energize the line relay 13 along a circuit as follows:

Circuit Number Twelve.

Commencing at the battery 20, conductors 60 100 and 123, armature 55 of the stick relay 17 in its upper position, conductors 124 and 65, armature 35 of the track relay 5 in its upper position, conductor 66, line relay 13 and conductors 67, 68, and 27 back to the common 105 wire 25.

When the line relay 13 is energized its armature 40 is raised to close the circuit Number Two and causes the signal 9 to assume its operated position, thereby permitting another following train to enter the block A.

It should be noted that the armature 56 of the stick relay 17 opens a break in the circuit Number Three for energizing the line 115 relay 15 so that said line relay 15 remains deenergized and the signals 11 and 12 controlled thereby will remain in their stop position until the maintaining circuit Number Seven for the stick relay is broken by 120 the energization of the line relay 14.

When the first pair of wheels and axle of the train enter the track section C, the track relay 7 is deenergized, and the armature 44 in dropping makes another break in the circuit Number Five for energizing the line relay 16, so that said line relay 16 will remain deenergized and the signal 12 will remain in its stop position after the train has 125 entirely left the track section B.

When the first pair of wheels and axle of the train enter the block D the track relay 8 is deenergized, and its armature 37 in dropping opens a break in the circuit Number Nine for energizing the line relay 14, so that said line relay will remain deenergized, and the signal 10 will remain in its stop position until the train has entirely left the block D. The armature 38 of the track relay 88 maintains the circuit Number Five for the line relay 16 broken and the signal 12 in its stop position until the train has entirely left the block D. The dropping of the armature 39 of the track relay 8 has no effect since the preliminary energizing circuit for the stick relay 18 is broken at the armature 52 of the line relay 15.

When the last pair of wheels and axle of the train leave the block D, the track relay 8 is reenergized and its armatures are raised to their upper position to restore all of the parts of the system to their normal positions.

When another train enters the stretch of track in the direction indicated by the arrow Y, the effect produced upon the different signals controlling traffic in the direction in which the train is traveling and in the opposite direction is substantially the same as the effect produced by the train traveling in the direction indicated by the arrow X; and the different circuits broken and established can be easily traced by analogy to the circuits already traced. When the train moving in the direction indicated by the arrow Y enters the block D, its wheels and axles shunt the track relay 8; and the armature 37 of said track relay 8 drops and interrupts the circuit Number Five for energizing the line relay 16, whereupon the armature 41 of said line relay 16 drops and interrupts circuit Number Six for the signal 12 and causes said signal 12 to assume its stop position. The armature 37 of the track relay 8 drops and interrupts the circuit Number Nine for energizing the line relay 14, and the armature 46 of said line relay 14 drops and interrupts the circuit Number Ten for the signal 10 and causes said signal 10 to assume its stop position. The armature 47 of the line relay 14 drops and interrupts the circuit Number One for energizing the line relay 13, whereupon the armature 40 of said line relay 13 drops and interrupts the circuit Number Two for the signal 9 and causes the signal 9 to assume its stop position.

From the foregoing it can be seen that when a train enters the stretch of single track traveling in the direction indicated by the arrow Y, the opposing signals 9 and 10 are placed at danger to furnish head-on protection for the train, and the signal 12 is placed at danger to afford following protection for the train.

When the armature 39 of the track relay 8 drops it closes a preliminary energizing circuit for the stick relay 18, said circuit being as follows:

Circuit Number Thirteen.

Commencing at the battery 22, conductors 95, 110, and 125, armature 39 of the track relay 8 in its lower position, conductors 126 and 127, armature 52 of the line relay 15 in its upper position, conductors 128 and 129, stick relay 18, conductors 130, 82, and 31 back to the common wire 25.

When the stick relay 18 is energized its armature 57 is raised to complete a maintaining circuit for said relay as follows:

Circuit Number Fourteen.

Commencing at the battery 22, conductors 95, 110, and 125, armature 39 of the track relay 8 in its lower position, conductors 126, 131, and 132, armature 57 of the stick relay 18 in its upper position, conductors 133 and 129, stick relay 18 and conductors 130, 82, and 31 back to the common wire 25.

As the train progresses and enters the track section C, the track relay 7 is shunted and its armatures 44 and 45 drop to their lower positions. The armature 44 opens another break in the circuit Number Nine for energizing the line relay 14, thereby holding the signals 9 and 10 in their stop positions. The armature 45 of the track relay 7 drops and interrupts the circuit Number Three for energizing the line relay 15, and the armature 50 of said line relay, in dropping, breaks the circuit Number Four for the signal 11 and causes said signal 11 to assume its stop position. The armature 53 of the line relay 15 in dropping closes another maintaining circuit for the stick relay 18 as follows:

Circuit Number Fifteen.

Commencing at the battery 21, conductors 83, 84, and 134, armature 53 of the line relay 15 in its lower position, conductors 135 and 132, armature 57 of the stick relay 18 in its upper position, conductors 133 and 129, stick relay 18 and conductors 130, 82, and 30 back to the battery 21.

The foregoing circuit Number Fifteen maintains the stick relay energized as long as the line relay 15 is deenergized, and from circuit Number Three it can be seen that the line relay 15 will remain deenergized until the train has passed through the entire length of the stretch and has left the block A. When the train in question moving in the direction indicated by the arrow Y passes from the block D into the track section C and deenergizes the line relay 15, the armature 51 of said line relay 15 opens another break in the circuit Number Five for energizing the line relay 16, and would hold the signal 12 at danger if it were not for

the stick relay 18, but when said stick relay 18 is energized its armature 58 is raised to establish a shunt, comprising conductors 136 and 137, for the contacts of the armature 51 of the line relay 15 so that, in spite of the fact that the line relay 15 is deenergized, the line relay 16 can be energized to cause the signal 12 to assume its operated proceed position by a circuit as follows:

10

Circuit Number Sixteen.

Commencing at the battery 21, conductors 83 and 137, armature 58 of the stick relay 18 in its upper position, conductors 136 and 15 91, armature 38 of the track relay 8 in its upper position, conductor 92, line relay 16 and conductors 93, 94, and 33 back to the common wire 25.

It should be noted that when the train 20 enters the stretch of track traveling in the direction indicated by the arrow X, the signal 9 assumes its proceed position as soon as the train entirely leaves the block A; but when the train is traveling in the direction 25 indicated by the arrow Y, the signal 9 assumes its stop position as soon as the train enters the block D and does not assume its proceed position until the train has traversed the entire length of the stretch and 30 has left the block A. In both cases the train was on the track section B at some one time; but in one case when the train is traveling in the direction indicated by arrow X, the presence of the train on the track section 35 B causes the signal 9 to assume its proceed position, whereas in the other case, when the train is traveling in the direction indicated by the arrow Y the presence of the train on the track section B holds the signal 40 9 in its stop position. These different controlling effects on the signal 9 produced by the track relay 6 of the track section B, depending upon the direction in which the train is traveling when it enters the track 45 section B, is due to the operation of the stick relay 17, and since the more significant features of this invention reside in the controlling circuits for the stick relays 17 and 18, these controlling circuits for the stick relay 50 17 have been drawn in heavy lines, it being noted that the controlling circuits for the stick relay 18 are the same. Referring to these circuits drawn in heavy lines it can be seen that the preliminary energization of 55 the stick relay 17 is dependent upon the condition of the track relay 5 and the line relay 14, the energizing circuit for said relay being established when the track relay 5 is deenergized and the line relay 14 is energized. The line relay 14 is controlled by the track relay 6 of the track section B, and is deenergized when said track relay is deenergized. In short, if the train enters the 60 block A from the track section B the stick

relay 17 is not energized, but if the train 65 enters the block A from the other direction, and said track section B is not occupied by another train, the stick relay 17 is energized. When the stick relay 17 is energized by the dropping of the armature 35 of the track 70 relay 5, a maintaining circuit is immediately established, said maintaining circuit being controlled independently of the armature 48, of the line relay 14 which is included in the preliminary energizing circuit for said stick 75 relay 17. When the line relay 14 is deenergized its armature 49 establishes another maintaining circuit for the stick relay 17, so that said stick relay 17 remains energized until said line relay 14 is reenergized. During the time that the armatures of the line 80 relay 14 are dropping and during the time that the preliminary energizing circuit 5 for the stick relay 17 is broken and before the other maintaining circuit Number Eleven 85 for said stick relay is established, said stick relay is held up by the first maintaining circuit Number Eight. This particular arrangement of two maintaining circuits may be eliminated if make-before-break contacts 90 are used so that the armature 49 contacts with the conductor 119 before the armature 48 breaks contact with the conductor 103 when the line relay 14 is deenergized. Other features of the controlling circuits can be 95 readily seen without being specifically pointed out.

In case two trains moving in opposite directions should happen to enter the blocks A and D simultaneously both the signals 10 100 and 11 would be placed in their stop positions, so that each train would receive head-on protection.

Although the particular embodiment of the invention shown is designed to be operated by direct current, simple modifications, which will be apparent to those skilled in the art of railway signaling, may be made whereby alternating current may be used as the operating medium. Also, the number of 105 track sections into which the stretch of single track is divided may be different according to different conditions; and other signals protecting the sidings, preliminary sections, and other different expedients known in the 110 art of railway signaling may be combined with this invention without departing from it or from the particular physical embodiment thereof shown and described.

Although I have particularly described 120 the construction of one physical embodiment of my invention, and explained the operation and principle thereof; nevertheless, I desire to have it understood that the form selected is merely illustrative, but does not 125 exhaust the possible physical embodiments of the idea of means underlying my invention.

What I claim as new and desire to secure by Letters Patent of the United States, is:

1. In a signaling system for railways, in combination; a stretch of trackway; a signal for governing traffic in one direction over said stretch, said stretch being divided into a first block protected by said signal and a second block following said first block, each of said blocks being track circuited and having a track relay; a circuit for controlling said signal; a circuit controller included in said controlling circuit and controlled by the track relay of said second block so as to be opened when said track relay is deenergized; a normally open shunt for the contacts of said circuit controller; a relay having coöperating contacts operated thereby which are included in said shunt and which are closed when said relay is energized; a preliminary energizing circuit for said relay controlled jointly by the track relays of said first block and said second block and closed when the track relay of said first block is deenergized and the track relay of said second block is energized; a maintaining circuit for said relay including coöperating contacts operated by said relay itself and closed when said relay is energized; said maintaining circuit being a branch of said preliminary energizing circuit and being controlled by the track relay of said first block independently of the track relay of said second block; another circuit controller controlled by the track relay of said second block and closed when that track relay is deenergized; and another maintaining circuit for said relay including said coöperating contacts thereof and said another circuit controller.
2. In a block signal system for railroads having tracks divided into track sections each having a track relay, a signal, a line circuit controlled by the track relays of a plurality of track sections in advance of the signal, a stick relay, an energizing circuit for the stick relay controlled by said line circuit and the track relay of a track section next in the rear of said signal, a preliminary stick circuit controlled by said rear track section, a final stick circuit controlled by said line circuit, and a circuit for controlling a signal in the rear governed by the line circuit and the stick relay jointly.
3. In a block signal system for single track railroads, three adjacent track sections each having a track relay, a stick relay, a pick-up circuit for the stick relay controlled by the track relays of two adjacent track sections, a preliminary stick circuit controlled by one of said two track relays, and a final stick circuit controlled by the other of said two track relays and the track relay of the third track section.
4. In a signaling system for railways, in combination; a stretch of trackway divided into a first and a second track circuited block each having a track relay; a signal at the entrance to the first block for governing traffic in one direction; a circuit controller controlled by the track relay of said second block and opened when said track relay is deenergized; a circuit for controlling said signal including said circuit controller; a normally open shunt circuit for the contacts of said circuit controller; a relay having coöperating contacts operated thereby which are included in said shunt circuit and which are closed when said relay is energized; a preliminary energizing circuit for said relay; and a maintaining circuit for said relay including said coöperating contacts operated by the relay itself and closed when said relay is energized, said maintaining circuit being controlled by the track relay of said first block independently of the track relay of said second block.
5. In a signaling system for railways, in combination: a stretch of track divided into track circuit sections; a signal for governing traffic over said stretch and protecting a predetermined portion thereof; a signal circuit for said signal controlled by the track relays associated with said portion of the stretch; a circuit controller included in said signal circuit and controlled by the track relays of another portion of said stretch in advance of said first mentioned portion in the direction in which said signal governs traffic; a shunt for said circuit controller; a stick relay for closing said shunt when energized; an energizing circuit for said stick relay which is closed when said first mentioned portion of the stretch is occupied and said second mentioned portion is not occupied; a preliminary stick circuit for said stick relay which is closed when said first mentioned portion of the stretch is occupied and said stick relay is energized; and another stick circuit for said stick relay which maintains said stick relay energized after it has been preliminarily energized so long as any part of said second mentioned portion of the stretch is occupied by a train.
6. In a signaling system for railways, in combination: a relay, two circuit controllers; an energizing circuit for said relay including said circuit controllers; coöperating contacts operated by said relay and closed when it is energized; a maintaining circuit for said relay including said coöperating contacts and one of said circuit controllers; a third circuit controller; another maintaining circuit for said relay including its coöperating contacts and said third circuit controller; means for simultaneously operating said third circuit controller and the one of said two circuit controllers which is not included in said first maintaining circuit; and a circuit for signaling controlled by said relay.
7. In a signaling system for railways, in

- combination: a stretch of track divided into track circuit sections; signals located at intervals along said stretch for governing traffic in opposite directions; a signal relay 5 associated with each signal; a signal circuit for controlling each signal relay which is controlled by the track circuit sections protected by the corresponding signal and also by the signal relay of the signal next in advance governing traffic in the same direction; an auxiliary relay associated with each intermediate signal for controlling the signal circuit of the signal next in the rear independently of the signal relay of that intermediate signal; means associated with each auxiliary relay for preliminarily energizing it when a train traveling in the direction of traffic governed by the corresponding signal occupies a track circuit section in 10 the rear of the corresponding signal prior to occupying a track circuit section in advance of the corresponding signal; and means for maintaining said auxiliary relay energized after it has been preliminarily energized by said last mentioned means while a train occupies said track circuit section in the rear and also the track circuit sections in advance of the corresponding signal and protected thereby.
- 15 8. In a signaling system for railways, in combination: a plurality of track circuit sections; a line relay controlled by certain of said track circuit sections; a circuit controller controlled by said line relay; a second circuit controller governed by a track circuit section in the rear of said certain track sections; a stick relay; an energizing circuit for said stick relay including said circuit controllers; a preliminary stick circuit for 20 said stick relay including said second circuit controller; a third circuit controller governed by said line relay and closed when that relay is deenergized; another stick circuit including said third circuit controller; and a circuit for signaling controlled by said 25 stick relay.
9. In a railway signaling system, a plurality of track circuit sections, a normally closed circuit controller opened when either of two particular track circuits is shunted, 30 a normally open circuit controller governed by a track circuit adjacent to said particular track circuits, a stick relay, an energizing circuit for the stick relay including said circuit controllers in series; a shunt for the normally closed circuit controller established by the energization of the stick relay, and means for maintaining said stick relay energized after it has been initially energized so long as either of said two particular track 35 circuits is shunted.
10. In a railway signaling system, the combination with a stretch of track divided into track circuit sections, signals at intervals for governing traffic in one direction, 40 a signal circuit for each signal, a stick relay associated with an advance signal for controlling the signal circuit of the signal next in the rear, means for energizing the stick relay of said advance signal upon the approach of a train thereto which is traveling in said direction of traffic, and separate means for maintaining said stick relay energized which are operated successively by such train, one means being operated as the 45 train approaches the advance signal, and the other means after the train has passed that signal.
